UNITED STATES PATENT OFFICE.

JEAN BAPTISTE DAUDELIN, OF FALL RIVER, MASSACHUSETTS.

SHUTTLE.

1,370,416.

Specification of Letters Patent.

Patented Mar. 1, 1921.

Application filed April 10, 1920. Serial No. 372,931.

To all whom it may concern:

Be it known that I, JEAN B. DAUDELIN, a citizen of the United States, residing at Fall River, county of Bristol, Commonwealth of Massachusetts, have invented certain new and useful Improvements in Shuttles, of which the following is a specification.

This invention relates to hand threading shuttles and involves certain improvements 10 in the construction of the threading eye whereby to provide for tensioning the thread and to prevent ballooning or dethreading.

My invention consists in the novel construction and combination of parts described 15 and illustrated in the accompanying specification and drawings and particularly pointed out in the appended claims. Throughout the specification and drawings like reference characters are correspondingly employed, and in the drawings:

Figure I, is a partial plan view of the threading end of a shuttle in accordance with my invention.

Fig. II is a side view thereof.
25 Fig. III. is a section on the line III—III, Fig. I.

Fig. IV is a detail view of the threading eye removed.

Fig. V is a section on the line V—V, Fig. 30 IV, and

Fig. VI is a detail view of the tensioning post removed.

I have indicated at 1 a hand threading shuttle of standard type having the usual 35 threading passages 2 and 3 and threading eye 4.

Set within the eye 4 is a bushing comprising tubular end sections 5 and 6 connected by a central web 7 and slotted along their 40 underface as indicated at 8. The bushing is positioned within the eye by means of an attaching tongue 9 which is bent across the outer end of the section 5 and is adapted for penetrative lodgment in the wood of the 45 shuttle.

Across the inner end of the section 5 a tensioning tongue 10 is bent down from the web portion 7 of the bushing and co-operates with a tensioning post 11 which is driven vertically from above into the eye and intersects the bushing adjacent said tongue 10, the bushing being cleared away as indicated at 12 to accommodate the post 11. The tensioning post 11 may be a simple spike having 55 a pointed penetrating end 13 and a rounded head portion 14. The wood at the

shuttle throat is vertically slotted as indicated at 15 to receive the post 11 which is in effect keyed in said slots 15. The head 14 has a tensioning eye 16 opening laterally 60 into the threading passage 2 as indicated at 17. The thread T from the bobbin enters said eye and is drawn over the lower wall 18 thereof, which thus acts as a tensioning bar, and from said bar 18 runs under the tensioning tongue 10 of the bushing and out through the end section 5 thereof. By varying the position of the post 11 relative to the bushing, the tension on the thread may be changed as desired.

The portion 19 of the head 14 overlying the eye 16 and spaced from the tensioning tongue 18 by the lateral kerf 17 acts as a guard to prevent ballooning of the thread during the run of the shuttle, and preferably has its upper surface developed on a curve as shown, to facilitate the entrance of the thread into the laterally opened eye 16. In assembling, the eye piece 6 is lodged in the shuttle-eye 4 with its attaching finger 9 80 embedded in the wood of the shuttle and its tensioning tongue 10 disposed across the shuttle eye. The post 8 is then driven vertically through the shuttle eye from above to position its tensioning tongue 18 above 85 and in a direction transverse to the direction of the tongue 10.

Various modifications in the construction and operation of my device may obviously be resorted to if within the limits of the 90 appended claims.

What I therefore claim and desire to secure by Letters Patent is:

1. In a shuttle, the combination with a tensioning element disposed transversely to 95 the axis of the shuttle eye and under which the thread runs, of an overlying tensioning element disposed parallel to the axis of the shuttle eye and over which the thread runs.

2. In a shuttle, the combination with a tensioning element disposed transversely to the axis of the shuttle eye and under which the thread runs, of an overlying tensioning element disposed parallel to the axis of the shuttle eye and over which the thread runs, 100 and a guard spaced from and overlying said last named tensioning element.

3. In a shuttle, an eye piece having a tensioning bar disposed transversely to the axis thereof, and under which the thread runs, 110 and a post having a tensioning bar disposed horizontally above said first-named tension-

ing bar and spaced therefrom and over which the thread runs to said first-named tensioning bar.

4. In a shuttle, a tubular eye piece having 5 a tensioning bar disposed transversely to the axis thereof, and under which the thread runs, and a post having a pointed entering end and a headed following end and having a tensioning bar disposed horizontally above 10 said first-named tensioning bar and spaced therefrom and over which the thread runs to said first-named tensioning bar.

5. In a shuttle having a threading eye and a threading passage leading thereto, a bushing in said eye provided with a tensioning 15 element, and a post driven into the shuttle from above said threading eye and having a laterally slotted head providing a tensioning eye disposed above and spaced from 20 said tensioning element of the bushing.

6. A tensioning element for a shuttle eye consisting of a member adapted to be driven into the shuttle from above the shuttle eye and having a slotted head providing a tensioning 25 element.

7. A tensioning element for a shuttle eye consisting of a member adapted to be driven into the shuttle from above the shuttle eye and having a tensioning eye.

30 8. A tensioning element for a shuttle eye consisting of a member adapted to be driven into the shuttle from above the shuttle eye and a tensioning bar and a guard overlying said bar to prevent ballooning of the thread 35 running over said bar.

9. In a shuttle, an eye-piece having a tensioning element, under which the thread runs and a tensioning element over which the thread runs disposed above and in a direction 40 transverse to the direction of said first-named tensioning element.

10. In a shuttle, an eye-piece having a tensioning element under which the thread runs, a tensioning element disposed above 5 and spaced from said first named tension-

ing element, over which the thread runs, and a guard spaced from and overlying said second-named tensioning element, and effective to prevent ballooning of the thread running over said second named tensioning 50 element.

11. In a shuttle, the combination with a tensioning element disposed horizontally of the shuttle eye and under which the thread runs, of a member set vertically of the shuttle eye and having between its ends a tensioning element disposed above said first named tensioning element and over which the thread runs to said first named tensioning 55 element.

12. In a shuttle, an eye piece having a horizontally disposed tensioning element under which the thread runs, and a horizontally disposed tensioning element fixed in the shuttle above and in spaced relation to 60 said first-named tensioning element and over which the thread runs to said first-named tensioning element, said tensioning elements extending substantially at right angles to each other in different planes.

70 13. A tensioning element for a shuttle eye, comprising a pointed member adapted to be driven into the shuttle and having a slotted portion between its ends providing a tensioning element over which the thread 75 runs.

14. A tensioning element for a shuttle eye, comprising a pointed member adapted to be driven into the shuttle and having a tensioning portion between its ends over which the thread runs and a guard spaced from and overlying said tensioning portion and effective to prevent ballooning of the thread running over said tensioning portion.

In testimony whereof I affix my signature 85 in presence of two witnesses.

JEAN BAPTISTE DAUDELIN.
